UNITED STATES PATENT OFFICE

2,615,483

SHAPER-SAW POWER FEED DEVICE

Hugh W. King, Corinth, Miss.

Application December 22, 1948, Serial No. 66,675

1 Claim. (Cl. 144—2)

1

This invention relates to a power feed device designed for use in connection with shaper-saws, and provides means for accurately feeding the stock through the knives and shapers of the machine in an absolutely straight path, without the services of an attendant in feeding the stock, thereby reducing accidents to a minimum.

An important object of the invention is to provide a device of this character which may be readily and easily mounted on a shaper fence, eliminating the necessity of making alterations in the usual shaper construction, to mount the device.

Another object of the invention is to provide a stock feeding attachment which is simple in design and capable of positive adjustment, insuring the accurate fast and safe operation of the saw or shaper with which the device is used.

A still further object of the invention is to provide a wood stock feeding device which will firmly hold the wood stock down on the shaper machine table, preventing slipping of the work which usually results in damage and scarring of the stock.

With the foregoing and other objects in view which will appear as the description proceeds, the invention consists of certain novel details of construction and arrangements of parts hereinafter more fully described and pointed out in the claim, it being understood that changes may be made in the construction and arrangement of parts without departing from the spirit of the invention as claimed.

Referring to the drawings

Figure 1 is a side elevational view of a power feeding attachment constructed in accordance with the invention, illustrating the attachment as mounted on the fence of a shaper-saw machine.

Fig. 2 is a plan view thereof the motor of the feed device having been removed.

Fig. 3 is a sectional view taken on line 3-3 of Fig. 2.

Fig. 4 is a side elevational view of the machine taken from the side opposite to Fig. 1.

Fig. 5 is a detail view illustrating the manner of mounting of the feed rollers of the device.

Fig. 6 is a sectional view taken on line 6-6 of Fig. 5.

Fig. 7 is a perspective view illustrating the table or support for the reduction gear box of the device.

Referring to the drawings in detail, the device forming the subject matter of this invention comprises a wide base 5 which is formed with a

depending flange 6 formed along one of its longitudinal edges, the flange cooperating with the bar 7 of the adjustable clamping device, in clamping the base to the fence of the woodworking machine with which the device is used, the fence in the present showing being indicated by the reference character 8.

A lug 9 extends downwardly from the lower surface of the base 5, and is formed with a threaded bore in which the threaded section 10 of the clamp 11 extends, the clamp 11 including the shank 12 which has swivel connection with the bar 7. The shank 12 also extends through an opening in the guide lug 13 which also depends from the lower surface of the base 5. A hand wheel indicated at 14 provides means whereby the shank 12 is rotated to move the bar 7 towards and away from the flange 6 to clamp or release the base from the fence 8 of the machine.

20 The base 5 provides a support for the motor
15 which includes a base plate through which
the bolts 16 extend, the bolts 16 also passing
through the openings 18 of the base 5, the open-
ings 18 being elongated so that an adjustment of
25 the motor 15 with respect to the base 5 will be
permitted to line up the gearing operated by the
motor.

30 Lugs 19 extend upwardly from the base plate, adjacent to one edge thereof, and these lugs are formed with threaded openings through which the bolts 20 operate, the bolts 20 engaging the base plate of the motor to secure the motor against movement after it has been properly positioned and adjusted on the base 5.

35 Extending forwardly from the base plate is a supporting plate 21 which is formed with openings 22 that align with openings formed in the reduction gear housing 23 for the reception of the bolts 24 that secure the reduction gear housing in position on the supporting plate 21. Extending into the reduction gear housing 23, is the driven shaft 25 that is operated by means of the belt 26 that operates over the pulley 27 secured to the shaft 25, the belt 26 also operating over the pulley 28 that is secured to the motor shaft 29.

50 The shaft 30 that extends from the reduction gear housing 23, provides a support for the sprocket 31 over which the chain 32 operates, the chain 32 also operating over the sprocket 33 secured to the shaft 34 so that rotary movement of the shaft 30 is directed to the shaft 34 and sprocket 33.

The shaft 30 operates in bearings 33' which
55 shaft also operates through bearings 34' and 35,

forming a part of the plates 36 and 37 respectively, the bearings 35 being disposed between the bearings 34', as clearly shown by Fig. 5 of the drawings.

The plate 36 is formed with elongated openings 38 that align with openings 39 of the plate 40 that carries bearings 41 in which the shaft 42 operates, the shaft 42 providing a support for the friction roller 43 which is constructed preferably of rubber, to grip the work to feed the work without slipping.

Cooperating with the plate 37, is the bearing plate 44 that has openings 45 for the reception of bolts that also pass through the elongated openings 46 of the plate 37 in securing the bearing plate 44 to the plate 37.

The bearings 47 extend from one edge of the plate 44 and support the shaft 48 on one end of which the friction roller 49 is secured to rotate therewith. The shaft 48 also supports the sprocket 50 at one of its ends over which sprocket the chain 51 operates, which chain also operates over the sprocket 52 that is secured to the outer end of the shaft 30.

The chain 53 operates over the sprocket 34 secured to shaft 30, and also operates over the sprocket 54 secured to the shaft 42. Thus it will be seen that due to this construction, the friction or feed rollers 43 and 49 will be rotated in the same direction to feed the wood stock to the woodworking tool of the machine by frictional contact therewith.

Due to the elongated openings of the plates 36 and 37, it will be obvious that adjustment of the bearing plates 40 and 44 may be had, to adjust the positions of the feed rollers 43 and 49. It will also be noted that the shafts 42 and 48 may be slightly adjusted angularly in a horizontal plane and with respect to the fence of the woodworking machine, to cause the feed rollers 43 and 49 to urge the stock under treatment, into close engagement with the fence 8 of the woodworking machine insuring a true operation of the woodworking tool 55 of the machine.

Rising from the supporting plate 21, is the post 56 which has a right angled end 57 bolted to the plate 21 by means of the bolt 58, the upper end of the post 56 extending at right angles providing the flange 59 formed with an opening through which the threaded shank 60 operates, the shank 60 being provided with the operating bar 61 and handle 62 by means of which the bar 61 and shank 60 are rotated.

The shank 60 extends through the nut 63 that is welded to the under side of the cross bar 64 directly under an opening which is in alignment with the threaded shank 60. A reinforcing flange 65 extends downwardly from one longitudinal edge of the cross bar 64 bracing the cross bar against bending under excessive strain.

Formed in the cross bar 64 adjacent to the ends thereof are openings in which the bolts 66

operate, the bolts 66 also operating through openings formed in the inwardly extended ends 67 of the upstanding bars 68, the bars 68 being pivotally connected with the plates 40 and 44 respectively so that vertical pivotal movement of the plates 40 and 44 will be permitted and guided.

Coiled springs 69 are mounted on the bolts 66 with their upper ends bearing against the cross bar 64, the lower ends thereof resting on the ends 67. This construction permits of vertical movement of the rollers 43 and 49 under the pressure of the springs 69, to hold the feed rollers to their work.

From the foregoing it will be seen that due to the construction shown and described, I have provided a stock feeding means for use in connection with shaper-saws or other woodworking machines, so that the work under treatment will be fed evenly and accurately to the woodworking tool of the machine, without danger of the work moving laterally from a given path, and without danger of injury to the hands of the operator.

It will also be seen that the device may be readily and easily clamped onto the fence of the usual woodworking machine without the necessity of using tools such as wrenches or the like to secure the attachment.

Having thus described the invention, what is claimed is:

In a power stock feeding device, a base, means for securing the base to the fence of a wood working machine, a pair of stationary plates having bearings, mounted on the base, a shaft operating in said bearings, said stationary plates extending laterally from the shaft in opposite directions, said stationary plates have elongated openings, independent adjustable plates having openings fitted on the stationary plates in overlapping relation therewith, bolts extending through the openings of said overlapping plates securing the stationary plates and adjustable plates together, whereby the adjustable plates are adjusted to various angular positions with respect to the stationary plates, pressure roller shafts mounted on the adjustable plates, rubber faced pressure rollers mounted on the shafts, adapted to engage and feed stock through the machine, and means for rotating said pressure rollers.

HUGH W. KING.
